(57) **CLAIM**

The ornamental design for a light strand support bracket, as shown and described.

DESCRIPTION

FIG. 1 is an isometric view of a light strand support bracket showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof showing my design; and,

FIG. 8 is an enlarged partial perspective view of light strand support bracket in an environment of use with non-claimed environmental structure shown in dashed lines.

The broken lines in FIG. 8 of the drawings depict environmental portions of the light strand support bracket which forms no part of the claimed design.
